HIGH-VOLTAGE RECTIFYING SYSTEM

Charles G. Smith, Medford, Mass., assignor to
Raytheon Manufacturing Company, Newton,
Mass., a corporation of Delaware

Application March 28, 1934, Serial No. 717,734

9 Claims. (Cl. 175—363)

This invention relates to a high-voltage rectifying system of the type utilizing space discharge tubes.

One of the objects of my invention is to devise 5 a system using space discharge tubes which are capable of withstanding inverse voltages of high values.

A further object of my invention is to devise 10 such a system in which the drop through the space discharge tubes in the conducting direction is substantially unaffected.

The foregoing and other objects of my invention will be best understood from the following 15 exemplifications thereof, reference being had to the accompanying diagrammatic drawings, wherein:

Fig. 1 represents schematically a single-phase rectifying system embodying my invention; and

Fig. 2 represents schematically a full-wave rectifying system also embodying my invention.

In rectifying systems it is desirable that such 20 systems be capable of rectifying very high voltages. Therefore, the individual rectifying units must be capable of withstanding these high voltages in the non-conducting direction so as to prevent the passage of any appreciable current 25 during the inverse cycle. Difficulties have been encountered in systems of this kind, particularly those using gaseous discharge rectifiers in which 30 "flash-back" or heavy surges of current in the reverse direction would occur when voltages greater than a certain value were applied across the gaseous discharge rectifiers. The voltage which such a system could rectify had to be considerably below that value. In accordance with 35 my present invention, I have devised a system whereby gaseous discharge tubes may be used in such a rectifying system, and withstand much higher voltages than could ordinarily be applied 40 to such devices.

In Fig. 1 I have shown such a gaseous discharge rectifier 1 having a thermionic cathode 2, and an anode 3, enclosed within a sealed envelope, such as a glass tube 4. The tube 4 contains 45 some suitable gas or vapor, such as, for example, mercury vapor which may be furnished from a small quantity of mercury 5. The cathode 2 and anode 3 are spaced apart within the envelope 4, and are adapted to support an ionizing discharge between them through the mercury vapor. Surrounding the discharge path between the cathode 2 and the anode 3 is placed a tubular 50 conducting member 6. The member 6 tends to create a substantially field-free space in the discharge path in which the discharge can readily be

controlled by a magnetic field. The tubular conducting member 6 is connected to the anode 3 through a high resistance 7. Some suitable means is also provided for creating a magnetic field transverse to the discharge path between the cathode 2 and anode 3 across the space surrounded by the tubular member 6. This means may consist of a coil 8 wound on a magnetic core 9 and disposed external to the tube adjacent the portion surrounding the tubular member 6. The cathode 2, anode 3, and member 6 can take a wide variety of forms. For example, member 6 can be either solid or perforated, and only partly surround the discharge space adjacent to it. In some cases member 6 can be left 15 out altogether.

The particular gaseous discharge rectifier, illustrated by way of example in Fig. 1, is disclosed and claimed in the copending application of Percy L. Spencer, Serial No. 612,235, filed May 19, 20 1932. In said application a more complete description of this type of rectifier will be found.

I have found that the above rectifier will prevent discharges in the reverse direction between the anode and the cathode even under the application of very high voltages when a transverse magnetic field is set up in the space surrounded by the tubular member 6. I have also found that when the magnetic field in this space is substantially zero, the voltage drop in the conducting direction in the cathode 2 and anode 3 can be very low, and the presence of the tubular member 6 and its associated structure does not materially affect the drop through the tube in the conducting direction. In order to utilize this 25 tube for increasing the inverse voltage which can be applied to such a tube, I have devised a novel system, one embodiment of which is shown for example in Fig. 1. The tube may be connected in the usual rectifying system which may comprise 30 a transformer 10 having a primary winding 11 connected to a source of alternating current, and a secondary winding 12 one end of which is connected to the cathode 2 and the other end of which is connected through a load or output device 13 to the anode 3. The cathode 2 may be supplied with heating current through a portion 35 40 45 50 55 60 65 70 75 80 85 90 95 100 105 110 115 120 125 130 135 140 145 150 155 160 165 170 175 180 185 190 195 200 205 210 which can vary the phase between the voltage at its output and the voltage at its input terminals in any desired manner is connected to the secondary winding 12. The output terminal of the phase-shifting device is connected to the primary 16 of a small auxiliary transformer 17. The secondary 18 of this transformer is connected through an auxiliary rectifier 19 to the coil 8.

10 The operation of the device shown in Fig. 1 is substantially as follows. When the voltage applied across the rectifier 1 is in such a direction that the cathode 2 is negative and the anode 3 is positive, an intense ionizing discharge will 15 pass between these two electrodes and current will flow through the output or load device 13. During this part of the voltage cycle, the rectifier 18 which is connected in series with the coil 8 will prevent current from flowing through the 20 coil 8, and thus no magnetic field will exist in the space enclosed by the tubular member 6. Thus substantially no resistance to the passage of the discharge between the cathode and anode is exerted by the tubular member 6 and its associated 25 structure during the conducting cycle of the space discharge device 1. As soon as the voltage across the space discharge device 1 reverses in direction, the voltage across the secondary 17 of the transformer 16 likewise reverses 30 in direction and the rectifier 18 will pass current which will flow through the coil 8. Thus a magnetic field will be set up transversely to the discharge path between the cathode 2 and the anode 3 within the space surrounded by the tubular 35 member 6, and effectively prevent the starting of any discharge between the cathode and anode. I have found that a comparatively small magnetic field during this portion of the cycle will permit the application of very high voltages between 40 the anode 3 and the cathode 2 without any substantial discharge taking place through the space between these two electrodes. In order that the magnetic field set up by the coil 8 shall have been built up to the proper value during the 45 inverse voltage cycle applied to the space discharge device 1, I have found that it is desirable to have some means for adjusting the time relationship between the magnetic field and the voltage applied to the space discharge tube. I have found that a convenient way of adjusting this 50 time relationship is to utilize a phase-shifting device, such as that illustrated at 15. By adjusting the voltage phase at the output terminals of this phase-shifting device, the time of building up 55 the magnetic field can be so controlled that the field is at the proper value to prevent the passage of a discharge before the inverse voltage across the space discharge device has been built up to an excessive value. As the inverse voltage 60 across the space discharge device decreases, the magnetic field likewise will decrease so that when the voltage again reverses and is impressed across the space discharge device in the conducting direction, the magnetic field set up by the 65 coil 8 will have disappeared, and thus offer no resistance to the starting of the discharge through the tube in the proper direction.

The arrangement shown in Fig. 1 can, of course, be adapted for use in rectifying systems in which a plurality of phases are rectified. In such a plural phase rectifying system, each phase would be provided with some such means as is shown in Fig. 1 to permit the application of very high inverse voltages without causing conduction in the inverse direction through the

rectifier. Of course other forms of plural phase rectifying systems could be used, and I have shown another modification of such a system in Fig. 2.

Fig. 2 shows a full wave rectifying system utilizing two rectifiers 20 and 21, each having a cathode 22, an anode 23, and a tubular conducting member 24 enclosed within the usual sealed envelope 25. The envelopes 25 likewise may contain a suitable gas or vapor, such as, for example, mercury vapor. Each of the tubular members 24 may be connected through a high resistance 26 to its respective anode 23. In a manner similar to that shown in Fig. 1, each of the rectifiers 20 and 21 is provided with means for creating a transverse magnetic field across the discharge space between the cathode and anode, and this means may consist of a coil 27 wound upon a magnetic core 28. The coil 27 and its associated rectifier so as to create a transverse magnetic field in the space surrounded by the tubular member 24. The two rectifiers shown in Fig. 2 may be connected in the usual full-wave rectifying system which may comprise a transformer 29 having a primary winding 30 connected to a source of alternating current and a secondary winding 31. The secondary winding is provided with a center tap 32 from which a connection passes through an output or load device 33 to both of the cathodes 22. Each of the cathodes 22 may be supplied with heating current in any suitable manner, such as, for example, by an auxiliary heating transformer 34. The outer ends of the secondary winding 31 are connected to the respective anodes 23 of the rectifying tubes 20 and 21. In series with each of the anodes is connected one of the coils 27. However, the connections are transposed so that the coil 27 associated with the rectifying device 20 is connected in series with the anode of the rectifying device 21, and likewise the coil 27 associated with the rectifying device 21 is connected in series with the anode of the rectifying device 20.

The operation of the device shown in Fig. 2 is substantially as follows. When the transformer 29 is energized, a voltage operates across the rectifying device 20 in such a direction so as to make the cathode negative and the anode positive, an intense ionizing discharge will pass between the cathode and anode, and current will flow through the output device 33. At the same time this current will likewise pass through the coil 27 associated with the rectifying device 21. During this time, in the rectifying device 21, the cathode is positive and the anode is negative. Since it is desirable to prevent current from passing through the rectifying device 21, during this part of the cycle it is desirable that a transverse magnetic field be set up within the tubular member 24 in order to prevent breakdown under the high inverse voltages which I contemplate using with such a system. As has been pointed out above, this is the condition which actually exists. When the voltage across the transformer 30 reverses, the current through the rectifying device 20 will cease, and likewise the magnetic field set up by the coil 27 associated with the rectifying device 21 will disappear, and thus the rectifying device 21 will be in condition to permit the passage of an intense discharge between its cathode and anode in the proper direction. When the rectifying device 21 starts to conduct current, it likewise will cause current to flow in the coil 27 associated with the 45 50 55 60 65 70 75 80 85 90 95

rectifying device 20, and prevent discharges in the inverse direction in said rectifying device 20 under the application of high inverse voltages. By properly designing the size of the coil 27 and its associated core 28, the magnetic field set up by these elements will be sufficient to enable the rectifying devices 20 and 21 to withstand extremely high inverse voltages without conducting current in the inverse direction.

Although I have shown rectifiers of the type in which rectification is dependent upon the temperature of the anode being comparatively low so that it does not emit electrons, my invention may also be used in devices in which the anode is not necessarily of this type. The anode, for example, can be made of a metal which under operation is raised to a sufficiently high temperature to emit electrons. Under these conditions the transverse magnetic field will effectively prevent conduction in the reverse direction, and comparatively high voltages may be impressed across the tube in the inverse direction without having substantial conduction of current through the tube in the reverse direction. In some instances it may be desirable to actually heat the electrode corresponding to the anodes shown in the figures. Under these conditions, by varying the phase of the transverse magnet field with respect to the voltage impressed across the tube, the tube may be made to reverse its direction of rectification, thus passing direct current in one or the other direction through the output circuit in accordance with the relationship of the transverse magnetic field to the applied tube voltage.

The invention is not limited to the particular details described above as many equivalents will suggest themselves to those skilled in the art. For example, the rectifying tubes which are used may be of any convenient type. The rectifying tubes in a plural phase rectifying system may be combined into a single tube in which each of the anodes has associated with it the proper means to resist conduction in the inverse direction. Also the means for preventing conduction in the inverse direction may take a wide variety of forms as will be apparent to those skilled in the art. It is accordingly desired that the appended claims be given a broad interpretation commensurate with the scope of the invention within the art.

What is claimed is:

1. A high-voltage rectifying system comprising a space discharge rectifier having a cathode and an anode adapted to support an ionizing discharge between them, control means interposed between said anode and cathode for preventing a discharge from passing between said cathode and anode, a source of alternating potential connected between said cathode and anode, and means for energizing said control means to prevent a discharge from passing throughout substantially the entire time when said anode is negative with respect to said cathode and for de-energizing said control means to render it inoperative to prevent a discharge from passing throughout substantially the entire time when said anode is positive with respect to said cathode.

2. A high-voltage rectifying system comprising a space discharge rectifier having a cathode and an anode adapted to support an ionizing discharge between them, auxiliary means for setting up a magnetic field in the discharge space between said cathode and anode for preventing a discharge from passing between said cathode and anode, and means for energizing said auxiliary means

when said anode is negative with respect to said cathode and for deenergizing said means when said cathode is negative with respect to said anode.

3. A high-voltage rectifying system comprising a space discharge rectifier having a cathode and an anode adapted to support an ionizing discharge between them, and a conducting member disposed adjacent to said discharge space, auxiliary means for setting up a magnetic field in the discharge space adjacent said conducting member for preventing a discharge from passing between said cathode and anode, and means for energizing said auxiliary means when said anode is negative with respect to said cathode and for deenergizing said means when said cathode is negative with respect to said anode.

4. A high-voltage rectifying system comprising a space discharge rectifier having a cathode and an anode adapted to support an ionizing discharge between them, control means interposed between said anode and cathode for preventing a discharge from passing between said cathode and anode, means for energizing said control means to prevent a discharge from passing when said anode is negative with respect to said cathode and for deenergizing said control means to permit a discharge to pass when said anode is positive with respect to said cathode, means for energizing said control means when said anode is negative with respect to said cathode and for deenergizing said means when said cathode is negative with respect to said anode, and means for adjusting the time relationship between said alternating potential and the energization and deenergization of said control means.

5. A high-voltage rectifying system comprising a space discharge rectifier having a cathode and an anode adapted to support an ionizing discharge between them, means for creating a substantially field-free space in the discharge space between said cathode and anode, auxiliary means for setting up a magnetic field in said field-free space between said cathode and anode for preventing a discharge from passing between said cathode and anode, and means for energizing said auxiliary means when said anode is negative with respect to said cathode and for deenergizing said means when said cathode is negative with respect to said anode.

6. A high-voltage rectifying system comprising a space discharge rectifier having a cathode and an anode adapted to support an ionizing discharge between them, auxiliary means for setting up a magnetic field in the discharge space between said cathode and anode for preventing a discharge from passing between said cathode and anode, said auxiliary means comprising a coil, means for energizing said coil, including a source of alternating current and a rectifier connected in inverse phase relation with respect to said space discharge rectifier.

7. A high-voltage rectifying system comprising a space discharge rectifier having a cathode and an anode adapted to support an ionizing discharge between them, auxiliary means for setting up a magnetic field in the discharge space between said cathode and anode for preventing a discharge from passing between said cathode and anode, said auxiliary means comprising a coil, means for energizing said coil, including a source of alternating current and a rectifier connected in inverse phase relation with respect to said space discharge rectifier, and an adjustable phase-shifting device for shifting the phase of the alternating potential applied to said rectifier.

8. A high-voltage rectifying system comprising two space discharge rectifier units, each having a cathode and an anode adapted to support an ionizing discharge between them, control means interposed between each anode and cathode for preventing a discharge from passing between said cathode and anode, a source of alternating potential connected between each cathode and anode, the control means for each rectifier unit being energized from the output of the other rectifier unit.
9. A high-voltage rectifying system comprising

two space discharge rectifier units, each having a cathode and an anode adapted to support an ionizing discharge between them, a source of alternating potential connected between each cathode and anode, auxiliary means for setting up a magnetic field in the discharge space between each cathode and anode for preventing a discharge from passing between said cathode and anode, said auxiliary means each comprising a coil, the coil for each rectifier unit being energized from the output of the other rectifier unit.

CHARLES G. SMITH.
